Primary Examiner—Elizabeth A Albert*Assistant Examiner*—Karen E Eldridge Powers(74) *Attorney, Agent, or Firm*—Law Offices of J. D. Geraigery; Janine D. Geraigery(57) **CLAIM**

The ornamental design for a hunter knit helmet, as shown and described.

DESCRIPTION

FIG. 1 is a perspective view of the helmet;

FIG. 2 is a right side view thereof;

FIG. 3 is a left side view thereof;

FIG. 4 is a front view thereof;

FIG. 5 is a back view thereof;

FIG. 6 is a bottom view thereof; and,

FIG. 7 is a top view thereof.

The stippling shown on FIGS. 1–4 and 6, the material framed by the thick, black edging, illustrates texture and forms a part of the claimed design.

The broken lines around the edges of the pocket in FIGS. 1 and 2 represent fabric stitching and form a part of the claimed design.
